UNITED STATES PATENT OFFICE.

WILLIAM H. RYTHON, OF SOMONAUK, ILLINOIS.

ROTARY FOR USE IN CONNECTION WITH WINDMILLS.

SPECIFICATION forming part of Letters Patent No. 278,748, dated June 5, 1883.

Application filed November 27, 1882. (No model.)

To all whom it may concern:

Be it known that I, WILLIAM H. RYTHON, a citizen of the United States, residing at Somonauk, in the county of De Kalb and State of Illinois, have invented certain new and useful Improvements in the Construction of Rotaries for Use in Connection with Windmills, of which the following is a specification.

Heretofore it has been impossible to successfully use a ratchet-wheel with pawls or dogs to operate the same in connection with windmill-rotaries, for the reason that the rapid and extended movement required in the pawl, together with the great pressure required to hold the pawl, in its downward movement, against the ratchet-wheel, so as to insure the catching of the same into the teeth of the ratchet-wheel in its upward movement, would rapidly wear the teeth on the face of the wheel smooth, and of such shape that the pawls or dogs would soon slip over the surface of said ratchet-wheel without causing the same to rotate. My invention affords a simple, cheap, durable, and safe method by which the reciprocatory motion of the pitman-rod of a windmill and the intermittent rotary motion of a ratchet-wheel used in connection therewith, and actuated thereby in such a manner as to allow of a short and slow vibratory movement in the arm carrying the pawl is converted into a constant rotary motion of the shaft on which said ratchet-wheel rotates and the machinery connected therewith; also, to provide means whereby the stopping of the machinery connected with said shaft by overwork or by the accidental elongating of the machinery may not break, injure, or interfere with the constant and regular motion of the wind-wheel and pitman-rod; also, to reduce to a minimum the wear of the pawl or dog actuating the ratchet-wheel and the teeth of said ratchet, as well as to render the working of said pawl and ratchet safe, durable, certain, and noiseless.

I have illustrated my invention by the accompanying drawings, making a part of this specification, in which Figure 1 is a plan view of the windmill-rotary of my improved construction, and showing a method of attaching the pitman-rod to the arm or pawl. I prefer to attach it to the pawl communicating motion to the ratchet-wheel. Fig. 2 is a cross-section

of the same on line 2 2 of Fig. 1. Fig. 3 is a section of the bearing in which the main shaft of my rotary revolves, and around or upon which the arms or arm carrying the pawl also rotates. Fig. 4 is a perspective view, showing the manner in which I may attach the pitman-rod of the windmill to the arm carrying the pawl or dog. Fig. 5 is a perspective view of the manner in which I attach the pitman-rod of the windmill to the pawl or dog in the place of attaching said pitman-rod to the arm carrying the pawl, as shown in Fig. 4. This is the method of construction which I prefer. Fig. 6 is a perspective view of the arms or levers shown in Fig. 2 with springs attached, by which I convert the intermittent rotary motion of the ratchet-wheel into a constant rotary motion of the shaft on which said ratchet-wheel rotates. Like letters refer to like parts throughout the several views.

A is the main shaft of the rotary, upon which the ratchet-wheel turns. B is the ratchet-wheel turning upon shaft A. b are the teeth of said ratchet-wheel B. C is the pawl or dog giving motion to ratchet-wheel B. c is the point of said pawl in connection with teeth b. D is the arm carrying the said pawl C. E E' are the bearings in which said shaft A turns. e is the continuation of said bearings E E', around which arm B partially rotates. F F' are rods attached to or a continuation of the pitman-rod. f is a plate to which said rods F F' are attached. G is the spring resting on said plate f, and compressed by the raising of said plate f when arm D is not raised. g is the plate against which the upper end of spring G presses, or by which it is held. H is a rod running through the center of spring G, and connected at point h with pawl C and at the other end with plate g. I is an arm or lever attached firmly to shaft A. K K' K'' K''' are arms or levers revolving loosely upon shaft A. L L' L'' L''' are springs separating said levers I K K' K'' K''' M is a stop on the face of wheel B, pressing against lever K. N is a stop or clutch preventing backward motion in wheel B. X X' is the frame-work supporting my improved windmill-rotary, and may be constructed of any suitable material.

The manner in which I accomplish the object or purpose of my invention is as follows:

Pitman-rod F F' is alternately raised and depressed by the action of the crank of the wind-shaft of the windmill. As the said rod is depressed point *c* of pawl C is raised or loosened from contact with teeth *b*, (when constructed as shown in Fig. 2.) Further depression of the pitman-rod causes arm B to rotate partially around on bearing *c' c'*. I prefer that the arc described by said arm D shall measure about 10 thirty degrees. The raising of the pitman-rod F F' may compress spring G sufficiently to allow the wind-wheel to complete the revolution without causing any upward motion in arm D. This occurs when the machinery connected with my rotary is overworked or accidentally clogged; and it is only at such times that said spring G is called upon to perform its functions. At other times the raising of pitman-rod causes pawl C to be raised in unison therewith, carrying with it arm D, causing said arm to partially rotate round bearings *c' c'*. It is obvious that before any upward movement can be communicated to pawl C by pitman-rod F F' when the same is attached to pawl C, as shown in Fig. 2, the said pawl is first firmly pressed against or into teeth *b* on ratchet-wheel B, and that, as at this precise moment the crank-shaft of the wind-wheel, which I have before called the "wind-shaft," is passing over its center, the movements of the pitman-rod F F' and point *c* of pawl C are very slow and easy, and no injury can be done to said pawl or to ratchet-teeth *b*. The upward movement of pawl C, as described, causes ratchet-wheel B to partially rotate (through an arc of about thirty degrees) upon shaft A. At the same time arm or lever K is forced forward through the same arc by means of stop M, shaft A remaining at rest, springs L L' L'' L''' are compressed, lever K K' K'' K''', each describing a less arc than the preceding lever, and lever I, remaining at rest with shaft A. When the forward motion of wheel B and lever K ceases they are held stationary by clutch M. Arm D and pawl C may be carried downward, repeating their former motion by the action of the pitman-rod F F'. Springs L L' L'' L''' regain their normal condition gradually, causing levers K K' K'' K''''' to revolve around shaft A, and lever I to revolve, carrying with it said shaft A. The action of these springs is such that a continuous rotary motion is given to said shaft A by means of lever I, said springs not having exhausted their force until they shall have received a fresh impetus or compression by the action of ratchet-wheel B through stop M, actuated by pawl C.

If the form of construction of the arm D, pawl C, and pitman-rod F F', with connecting-spring G, plates *f g*, and rod H (shown in Fig. 4) is used, it will be necessary to attach a weight or spring to pawl C to hold point *c* of said pawl against teeth *b* of ratchet-wheel B.

The windmill-rotary invented and constructed by me and here described possesses many advantages over any rotary heretofore made. The cost of my rotary is much less than

any other, it is more durable and acts with greater certainty, and the work which the wind-wheel has to perform can under no circumstances exceed a given number of pounds, which is regulated by the size and strength of spring G. This spring is of the same strength, requiring the same number of pounds to compress it, as the springs L L' L'' L''', and hence 70 the difference in leverage, resulting from the difference in length of the levers K, K', K'', K''', and I, and the length of the arm D, is the only excess of power required in case of the stopping of the machinery of the rotary, from 75 overwork or accidental clogging, as hereinbefore described, with arm D remaining at rest.

It is obvious that arm D may be pivoted at or about point *a* on frame X X' without in the least departing from my invention.

The arrangement or method of attaching the pitman-rod to the pawl shown in Fig. 5 insures a firm pressure of the pawl against the ratchet-wheel. So great is this pressure and so firm its hold that even a friction-clutch, 80 without the intervention of ratchet-teeth on the wheel, would operate the same, and such friction-clutch or smooth wheel in place of the teeth here shown would in no wise depart from or be other than my invention. In case arms D 90 D' are weighted, so that said arms shall remain stationary when turned at any point on bearings *c' c'*, the initial downward movement of the pitman-rod will actually raise point *c* of pawl C from the face of the ratchet-wheel. If 100 the arm is not weighted, however, point *c* will be pressed slightly against the face of the ratchet-wheel by the tendency of arms D D' to assume a perpendicular position on bearings *c' c'*. The main objects of my invention are, however, obtained by the arrangement of the levers I K, &c., and springs L L', &c., placed, with ratchet-wheel B, on shaft A, as hereinbefore described. By the use of these springs and levers I am enabled to convert the intermittent rotary motion of the wheel B into a continuous motion of the shaft A, and am further enabled, in a certain degree, to equalize the variable movements of the wind-wheel by the partial storage of power in said spring; 110 and produce, to a greater extent than has been heretofore attained, a constant and regular motion in the machinery connected with the rotary.

Having thus described my invention and 120 the manner of its construction and operation, what I claim, and desire to secure by Letters Patent, is—

1. A windmill-rotary comprising the following elements: a main shaft provided with 125 means for transmitting its motion to connecting-machinery, said shaft having a lever or arm firmly attached thereto, and other like levers or arms placed loosely thereon, all connected by springs, a loose pulley or wheel 130 placed on said shaft, actuating one of said loose levers or arms, said loose pulley or wheel having ratchet-teeth on the outer surface thereof, the whole being arranged, constructed, and

operated substantially as described, and for the purpose mentioned.

2. A windmill-rotary comprising the following elements: a main shaft provided with means for transmitting its motion to connecting machinery, said shaft having an arm or lever firmly attached thereto and other like arms or levers placed loosely thereon, all connected by springs, a loose pulley or wheel placed on said shaft actuating one of said loose arms or levers, said loose pulley or wheel having ratchet-teeth on the surface thereof, an arm placed loosely on said shaft, and carrying a pawl or dog connecting with said ratchet-teeth and operated by the pitman of the windmill, the whole being arranged, constructed, and operated substantially as described, and for the purpose mentioned.

3. A windmill-rotary having shaft A, ratchet-wheel B, arm or lever I, attached firmly to shaft A, arms or levers K K' K" K'', &c., revolving loosely upon shaft A, springs L L' L" L'', &c., separating said levers I K K' K" K'', &c., stop M on the face of wheel B, and stop or clutch N, all constructed in combination, substantially as and for the purpose mentioned.

4. Arm D, and pawl C, connected to the pitman-rod at point h, all combined and operated substantially as described.

5. Rods F F', plate f, spring G, plate g, and rod H, all combined substantially as described, and for the purpose mentioned.
